Primary Examiner—Alan P. Douglas*Assistant Examiner*—Jeffry H. Musgrave*Attorney, Agent, or Firm*—John P. McGonagle**[57] CLAIM**

The ornamental design for coin roll opener, as shown and described.

DESCRIPTION

FIG. 1 is a perspective view of a coin roll opener embodying my new design with portions broken away for clarity of illustration;

FIG. 2 is a top plan view thereof with portions broken away for clarity of illustration;

FIG. 3 is a bottom plan view thereof;

FIG. 4 is a left side elevational view thereof;

FIG. 5 is a front view thereof;

FIG. 6 is a rear view thereof; and,

FIG. 7 is a right side elevational view thereof.

The broken line showing of the table top is for illustrative purposes only and forms no part of the claimed design.
